(57) CLAIM

The ornamental design for an electronic housing with removable support stand, as shown and described.

DESCRIPTION

FIG. 1 is a front perspective view of an electronic housing with removable support stand showing our new design in a first state, and identifies a region for enlargement in FIG. 8;

FIG. 2 is a front view thereof;
FIG. 3 is a rear view thereof, and identifies a region for enlargement in FIG. 9;
FIG. 4 is a right side view thereof;
FIG. 5 is a left side view thereof;
FIG. 6 is a top view thereof, and identifies a region for enlargement in FIG. 10;
FIG. 7 is a bottom view thereof;
FIG. 8 is an enlarged view of the encircled portion in FIG. 1;
FIG. 9 is an enlarged view of the encircled portion in FIG. 3;
FIG. 10 is an enlarged view of the encircled portion in FIG. 6;
FIG. 11 is a front perspective view of an electronic housing with removable support stand showing our new design in a second state;
FIG. 12 is a front view thereof;
FIG. 13 is a rear view thereof;
FIG. 14 is a right side view thereof;
FIG. 15 is a left side view thereof;
FIG. 16 is a top view thereof; and,
FIG. 17 is a bottom view thereof.

The broken line showing of the various unshaded elements of the electronic housing and the removable support stand illustrates environmental structure and forms no part of the claimed design.
